DUST PREVENTION IN ROCK DRILLS

Ernest Marklow Mitchell, Bexley, New South Wales, Australia

Application April 11, 1934, Serial No. 720,106
In Australia May 30, 1933

3 Claims. (Cl. 255—49)

In the operation of rock drills, or picks as they are sometimes termed, particularly those of percussion type, a considerable quantity of dust results from the action of the bit on the rock or the like, and it is the object of this invention to prevent the dissemination of this dust in dry condition.

It is known to use water as a dust-laying medium but this practice is ineffective and results in an unnecessary and objectionable sloppiness at the scene of operation. My invention makes use of water in finely atomized form directed on to that part of the surface being operated upon which is adjacent to the bit.

The invention is applicable to pneumatically operated drills or picks of single unit hand manipulated type, or of multi-unit type, and it consists in providing means whereby the exhaust air is automatically charged with atomized water in regulated quantity and is directed on to and immediately about the part operated on by the bit to effect a dampening of the dust so that it does not readily rise.

According to this invention, there is connected to the exhaust pipe a nozzle which is itself connected to a valved water supply pipe, said nozzle being so constructed and arranged that a fine jet or spray of water is injected into the exhaust pipe in such manner that it is atomized by the rush of exhaust air, the exhaust pipe being extended towards the bit and preferably gradually increasing in diameter in order that the issuing blast is of less velocity than would otherwise be the case, and also that a wider distribution is obtained.

To more fully explain the invention reference will now be made to the accompanying drawing which depicts a practical embodiment of the invention and in which

Fig. 1 is an elevation of a standard type of pneumatic percussion drill or pick in operation, and equipped according to this invention;

Fig. 2 is an elevation to an enlarged scale partly in section showing the nozzle;

Fig. 3 is a sectional plan on line 3—3 of Fig. 2, and

Fig. 4 a sectional elevation on line 4—4 of Fig. 2.

Reference 1 indicates generally the pneumatic drill or pick coupled to an air supply hose 2, fitted with a bit 3 and having an exhaust pipe 4.

Fitted to the exhaust pipe is an elbow 5, and to this is coupled a T-piece 6. To one end of the T-piece there is connected an extension 7 of the exhaust pipe which is of gradually increasing

diameter. Screwed into the stem of the T-piece is the nozzle housing indicated generally by reference 8, and to the outer end of this is attached a regulating tap 9 to which is coupled the flexible water supply pipe 10.

The nozzle itself consists of a thin metal tube 11 flattened at its inner end as at 12 to form a narrow but horizontally lengthy slot 13 through which a flat jet or spray of water is projected into the T-piece in a direction perpendicular to the flow of the exhaust air. The tube 12 is sweated or otherwise secured in a double-ended coupling 8a which at its other end engages a screwed socket 8b to which the tap 9 is attached.

To minimize the risk of the narrow opening 13 becoming chocked with grit, a filter screen 14 is fitted to the outer end of pipe 11, and if necessary a similar but slightly coarser screen 15 is fitted to the inner end of tap 9.

It is to be understood that the slot or aperture 13 is of infinitesimal vertical width so that the injected water is in effect little more than a spray. By means of the tap 9 control of both quantity and pressure is obtained.

In operation the rush of exhaust air atomizes the injected water, carries it with it and delivers it in a fine spray as shown at 16 (Fig. 1) about the bit 3.

I claim:

1. In a pneumatically operated percussion rock drill, means for charging the exhaust air with moisture and directing it on to and about the bit, said means comprising a T-piece on the outer end of the normal exhaust pipe, an extension of the exhaust pipe of gradually increasing diameter beyond said T-piece and having its open end disposed to direct the exhaust air on to and about the bit, a water spray nozzle fitted to the branch of said T-piece and having its outer end formed for connection to a water supply pipe, said nozzle having a restricted outlet disposed to direct into the exhaust pipe a flat spray, means for regulating said spray, and water filtering means at the outer end of said nozzle.

2. In a pneumatically operated percussion drill or pick, means for charging the exhaust air with moisture in atomized condition and for directing it on to and about the bit, said means comprising a water spray nozzle coupled to a pressure water supply pipe and fitted to the air exhaust pipe to inject a spray of water thereinto, a valve on said supply pipe for regulating the quantity of water injected, and a detachable extension of the exhaust pipe beyond the water spray nozzle, said extension being of gradually increasing diameter.

to slow down the velocity of the issuing blast of air and widen its distribution, the open end of said extension being disposed to direct the moisture-laden air on to the working face about the bit.

5. 3. In a pneumatically operated percussion drill or pick, means according to claim 2 hereof for

charging the exhaust air with moisture in atomized condition and for directing it on to and about the bit, characterized in that the water spray nozzle is formed to produce a flat spray injected perpendicularly to the flow of air in the exhaust pipe.

5 ERNEST MARKLOW MITCHELL.
